Primary Examiner — Garth Rademaker

Assistant Examiner — Samantha Q Lawrence

(74) Attorney, Agent, or Firm — Kimberly-Clark
Worldwide, Inc.(57) **CLAIM**We claim the ornamental design for an absorbent article, as
shown and described.

DESCRIPTION

FIG. 1 is a top view of an absorbent article.

FIG. 2 is a first side view of the absorbent article of FIG. 1.

FIG. 3 is a back view of the absorbent article of FIG. 1.

FIG. 4

is a second side view of the absorbent article of FIG. 1;

and,

FIG. 5 is a first end view of the absorbent article of FIG. 1;

and,

FIG. 6 is a second end view of the absorbent article of FIG. 1.

The broken lines shown in FIGS. 2 and 4-6 illustrate
portions of the absorbent article that form no part of the
claimed design.**1 Claim, 2 Drawing Sheets**(56)
